TEA KETTLE OR SIMILAR ARTICLE

Michael Lax, 68 E. 91st St., New York, N.Y. 10028

Filed Dec. 23, 1969, Ser. No. 20,616

Term of patent 14 years

Int. Cl. D7—02

U.S. Cl. D44—25

FIG.1

FIG.2

FIG.3

FIG.4

FIG.5

FIG.6

FIG. 1 is a side elevational view of a tea kettle or similar article showing my new design;

FIG. 2 is a front elevational view.

FIG. 3 is a rear elevational view.

FIG. 4 is a top, plan view.

FIG. 5 is a cross section view taken on line 5-5 of FIG. 4; and

FIG. 6 is a reduced scale bottom plan view.

I claim:

The ornamental design for a tea kettle or similar article, as shown and described.
